RACKET PRESS

Laurance C. Doll, Ithaca, N. Y.

Application May 3, 1939, Serial No. 271,596

7 Claims. (Cl. 273—74)

This invention relates to certain new and useful improvements in racket presses.

The primary object of the invention is to provide a racket press for holding the string frame portion thereof against warpage or distortion when the racket is out of use and which accomplishes such objects with a greatly simplified construction that may be inexpensively manufactured.

10 A further object of the invention is to provide a racket press comprising a pair of press members pivotally connected together at a pair of corresponding ends in the absence of the usual intermediate connecting link member with the free 15 ends of the press members readily separable to permit unobstructed passage of the racket frame between the press members for placement therein, the construction of the press being such that the press members are movable into parallel position on the pivotal connections when out of use 20 for occupying a minimum of space for shipment or storage.

With the above and other objects in view that will become apparent as the nature of the invention is better understood, the same consists in the novel form, combination and arrangement of parts hereinafter more fully described, shown in the accompanying drawing and claimed.

In the drawing:—

30 Figure 1 is a top plan view of a racket press constructed in accordance with the present invention, the same being illustrated in holding or clamping engagement with the string frame of a racket illustrated by dotted lines;

35 Figure 2 is a side elevational view of the racket press;

Figure 3 is a top plan view of the racket press in its folded or collapsed portion with the two members thereof moved into parallel juxtaposition;

40 Figure 4 is a vertical cross sectional view taken on line 4—4 of Figure 2;

Figure 5 is a top plan view of another form of racket press embodying two pivotally connected 45 press members, the press members being illustrated by dotted lines in partially opened positions; and

Figure 6 is an end elevational view of the racket press shown in Figure 5.

50 The racket press comprises a pair of press members designated in general by the reference characters 10 and 11 respectively and each press member comprises a pair of bars 12 and 13, corresponding ends of the bars 12 and 13 of the two 55 press members 10 and 11 being pivotally connect-

ed together as indicated in general by the reference character 14. As shown in Figures 1 and 3, the opposed side edges of the press members 10 and 11 are straight as indicated at 15 so that when the press members are moved on their pivotal connection 14 toward each other, the same lie in parallelism and juxtaposed as shown in Figure 3 for occupying a minimum of space for storage or shipment. The outer edges 16 of the bars of the press members may be of any configurations or designs desired, the same being illustrated as reversely curved.

The pivoted ends of the bars 12 and 13 are cut away to provide interfitting ends 16 of tenon characteristic so that the two bars 12 and 13 of 15 the press members 10 and 11 respectively lie in the same plane as shown in Figure 4. The pivotal connection 14 comprises a threaded bolt 17 extending through the interfitting ends of the bars 12 and 13, the headed end 18 of the bolt 17 being engaged with the lower bars 13 while the threaded portion 19 of the bolt extends upwardly through the interfitting bars 12 for the reception of a wing nut 20. A coil spring 21 surrounds the bolt 17 between the upper and lower bars 12 and 25 13 for normally holding the bars in spaced relation. The outer free ends of the superposed bars 12 and 13 of the press members 10 and 11 are connected together by a threaded bolt 22 shown in Figure 2, as extending through said bars 12 30 and 13 with a coil spring 23 surrounding the bolt 22 and engaged with the bars 12 and 13, while a thumb nut 24 is threaded upon the upper protecting end of the bolt 22.

A racket frame 25 is illustrated in Figure 1 35 by dotted lines as held within the racket press, the racket frame 25 being located between the upper and lower bars 12 and 13 of the press members. When it is desired to place the racket press in engagement with the racket frame 25, the thumb nut 20 on the pivot bolt 17 connecting the two press members 10 and 11 is loosened so that said press members may be widely separated at their outer free ends so that no obstructions of any character are present 45 to hinder the placement of the racket frame between the bars 12 and 13 of the press members. The free ends of the press members are then moved toward each other until the bolts 22 are in proximity of the outer edges of the bracket 50 frame 25 at which time the thumb nuts 20 and 24 are tightened on respective screw bolts for holding the press engaged with the racket frame 25, as shown in Figure 1. The racket frame 25 is held against distortion and warping by the 55

press and as there is no connecting cross bar between the free ends of the press members 10 and 11, the first member may be easily and quickly engaged and disengaged from the racket frame without injury to the latter. The cost of manufacture is also greatly reduced by the elimination of the cross bar between the inner free ends of the press members and the elimination of the usual links connecting the outer pivoted 10 ends of the press members, the racket press merely comprising two bars directly pivoted together at corresponding ends when the press is disengaged from the racket and placed for storage or shipment, the straight edges 15 move into 15 abutting engagement as shown in Figure 3 so that the press occupies a minimum of space. The thumb nut 20 is then tightened on the pivot bolt 17 for holding the press members 10 and 11 in their engaged position and against accidental pivotal separating movement.

In the form of racket press shown in Figures 5 and 6, the top and bottom bars 12a and 13a are pivotally connected together at corresponding ends by means of top and bottom plates 25 25 and 26 respectively engaged with the outer faces of the bars 12a and 13a with each of the plates 25 and 26 having a pivot pin connection 27 with the bars 12a and 13a. To limit the pivotal connection of the bars 12a and 13a, each of said 30 bars carries a pin 28 extending through an articulate slot 29 in the adjacent plate 25 or 26 as shown in Figure 5, the opening and closing movements of the bars 12a and 13a on the pivotal connection 27 being limited by movement of the pins 28 carried by the bars and moving through the slots 29. The tensioned pivotal connection 14a 35 between the bars 12a and 13a extends through the plates 25 and 26 while the free ends of the bars 12a and 13a of each press member are 40 connected by tensioned bolts 22a.

From the above detailed description of the invention, it is believed that the construction and operation thereof will at once be apparent and while there are herein shown and described 45 the preferred embodiments of the invention, it is nevertheless to be understood that minor changes may be made therein without departing from the spirit and scope of the invention as claimed.

50 I claim:

1. A racket press comprising two press members directly pivotally connected together at corresponding ends and free of connections at their other ends, each press member including a 55 pair of bars, the pivotal connection including a clamping bolt for moving the bars into clamping engagement with a racket frame, clamping bolt associated with the free ends of the bars of each clamping member and spring means associated with the clamping bolts and bars for normally holding the bars of each press member separated for reception of a racket frame.

2. A racket press comprising two press members pivoted together at corresponding ends, 60 the opposed sides of the press members being straight for straight edge contact when moved on their pivotal connection towards each other, each press member including a pair of bars, the pivotal connections including a clamping bolt

for moving the bars into clamping engagement with a racket frame, a clamping bolt associated with the free ends of the bars of each clamping member and spring means associated with the clamping bolts and bars for normally holding the bars separated for reception of a racket frame. 5

3. A racket press comprising two press members directly pivotally connected together at corresponding ends, the opposed sides of the press members being straight for straight edge contact when moved on their pivotal connection towards each other for storage and/or shipment, and a tenon joint at the pivoted ends of said press members whereby said press members may be substantially moved into alignment so that a racket frame can be placed unobstructedly in position in the press. 15

4. A racket press comprising two press members directly pivotally connected together at corresponding ends and free of connections at their other ends, each press member including a pair of bars, the pivotal connections including a clamping bolt for moving the bars into clamping engagement with a racket frame, a clamping bolt 20 associated with the free ends of the bars of each clamping member, spring means associated with the clamping bolts and bars for normally holding the bars separated for reception of a racket frame, and a tenon joint at the pivoted ends of 30 said press member.

5. A racket press comprising two press members pivoted together at corresponding ends, the opposed sides of the press members being straight for straight edge contact when moved on their 35 pivotal connection towards each other, each press member including a pair of bars, the pivotal connections including a clamping bolt for moving the bars into clamping engagement with a racket frame, a clamping bolt associated with the free 40 ends of the bars of each clamping member, spring means associated with the clamping bolts for normally holding the bars separated for reception of a racket frame, and a pair of plates to which the respective pairs of bars are pivotally connected, 45 the clamping bolt at the pivoted end of said press member extending between said plates.

6. A racket press comprising two elongated press members directly pivotally connected together at corresponding ends, and abutment 50 shoulders on the pivoted ends of the press members adapted to engage each other when the elongated press members are widely separated at their free ends to facilitate placement of a racket therein and for limiting separating movements of 55 said press members.

7. A racket press comprising two elongated press members directly pivotally connected together at corresponding ends, and abutment 60 shoulders on the pivoted ends of the press members adapted to engage each other when the elongated press members are widely separated at their free ends to facilitate placement of a racket therein and for limiting separating movements of said press members, and said press members 65 having opposed straight edges adapted to be moved into abutting contact when out of use for occupying a minimum of space.

LAURANCE C. DOLL.
